Term of patent 14 years

(Cl. D10—8)

Figure 1 is a perspective view of a door latch operating unit, taken from one side thereof, showing my new design;

Figure 2 is a perspective view of the door latch operating unit, taken from the opposite side thereof;

Figure 3 is a plan view of the unit;

Figure 4 is a front view of the unit;

Figure 5 is a rear view of the unit;

Figure 6 is a left-hand end view of the unit, as shown in Figure 3; and

Figure 7 is a right-hand end view of the unit, as shown in Figure 3.

The essential features of the design reside in the solid line portions.

I claim:

The ornamental design for a door latch operating unit, as shown and described.
